UNITED STATES PATENT OFFICE.

MORRIS B. OKUN, OF CHICAGO, ILLINOIS.

BEDSTEAD-CORNER.

1,126,068.

Specification of Letters Patent.

Patented Jan. 26, 1915.

Application filed February 28, 1914. Serial No. 321,827.

To all whom it may concern:

Be it known that I, MORRIS B. OKUN, a citizen of the United States, residing at Chicago, in the county of Cook and State of Illinois, have invented new and useful Improvements in Bedstead-Corners, of which the following is a specification, reference being had to the accompanying drawings, forming a part thereof.

10 The purpose of this invention is to provide an improved construction of corner fitting for a metal bedstead.

It consists in the elements and features of construction shown and described, as indicated in the claims.

15 In the drawings:—Figure 1 is a perspective view of a bedstead corner embodying this invention, showing the angle iron side rail inserted with its horizontal flange at the top. Fig. 2 is a perspective view of a bedstead corner, showing the angle iron side rail inserted with its horizontal flange at the bottom. Fig. 3 is a longitudinal vertical section at the line, 3—3, on Fig. 1. Fig. 20 25 4 is a section at the line 4—4 on Fig. 3. Fig. 5 is a view similar to Fig. 3, showing the side rail mounted in reverse position from the preceding figures. Fig. 6 is a detail section at the line, 6—6, on Fig. 4. Fig. 7 is a 30 perspective view of the wedge fitting.

In the structure shown in the drawings, the corner joint fitting comprises a housing, A, which is made from a single piece of sheet metal blanked out in proper form and 35 folded in a manner which will be readily understood from Figs. 1 and 2 without specific description, the resulting housing being substantially a rectangular box having one vertical edge shaped to seat against the bed- 40 post, B, which in the drawing is represented as cylindrical, requiring the fitting, A, to have its vertical edge which seats against the post correspondingly concaved, as shown, and having the opposite edge aper- 45 tured to receive the inserted end of the side rail, C, so that the latter will seat in the upper outer corner of the box. The side rail, C, made as usual of angle iron, has one of its flanges cut back for a short distance 50 which need not exceed two inches at each end, reducing the width of that flange for that extent to about one-fourth its full original width. This reduced flange is indicated by the numeral, 3, in the drawings.

55 The other flange for a distance, 3^a, at each end, corresponding to the length of the

reduced portion, 3, of the other flange, is very slightly reduced, forming a shoulder, 3^b, in the same vertical transverse plane with the shoulder, 3^c, which results from the reduction of the other flange as described. Both of the flange portions, 3 and 3^a, are provided at their edges with one or more, (as illustrated, two), notches indicated by the numerals, 4, 4 on the flange, 3, and 4^a, 4^a, on 60 65 the flange, 3^a. These notches are designed for engagement of a locking and clamping device hereinafter described, and the provision of such notches in the edges of both flanges, 3 and 3^a, and at both ends of the side 70 rail, C, is designed for the purpose of adapting the rail to be secured in the housing either edge up,—that is, with the horizontal flange either at the top or at the bottom; and the provision of a plurality of notches 75 in each of the flange edges is designed for the purpose of adapting the rail to be engaged in the housing at as many different positions with respect to its depth of intrusion into the housing as there are notches in 80 each of the edges. The two notches shown in each edge being spaced apart, say a distance of one and one-fourth inches, each end of the rail may be inserted into its housing, either to the depth of the first notch or to 85 the depth of the second notch, thus rendering the bed frame adjustable to three different lengths, the shortest length being obtained when the rail has both ends inserted to the depth of the innermost notch, the 90 greatest length being obtained when both ends are inserted only to the depth of the outermost notch.

95 For locking and clamping the rail in the housing, there is provided a wedge device, D, which is made of metal bar folded to form a three-sided or staple-like figure, the two legs, d, of the staple being the wedge members, and the staple as a whole being adapted to be inserted up into the housing 100 from the lower side at the outer end, so as to occupy the lower outer corner of the housing box with the longer vertical edges of the wedge side bars, d, bearing against the inner vertical side, A¹, of the housing box, 105 A, as seen most clearly in Figs. 4 and 5. The cross bar, d¹, of the wedge device, D, has a bolt-hole, d², and a bolt, E, is provided adapted to be inserted down through the box from top to bottom, said bolt having a 110 square shoulder, E¹, adjacent to its head, and the hole for the bolt in the top side, A²,

of the housing box being squared to fit this shoulder to prevent the bolt from turning. Said bolt extending down through the housing and out through the hole, d^2 , in the 5 wedge device, D, is provided with a wing nut, F, screwed on to its lower threaded end for crowding the wedge device, D, up into the housing. In operation, the thumb nut is run down on the threaded end of the bolt 10 sufficiently to allow the wedge device, D, to drop its upper sloping edge low enough to admit the end of the rail, C, in either of the positions indicated; that is, with the horizontal flange either at the top or at the bottom, as respectively shown in Figs. 4 and 5. The sloping edge of the wedge sides, d, is jogged or offset so as to constitute two separate slopes, d^3 and d^4 , the latter in position to bind against the edge of the horizontal 15 flange when the rail, C, is inserted with that flange at the lower side, as shown in Fig. 5, and the latter, d^4 , being in position to engage the lower edge of the vertical flange of the rail when the latter is inserted with 20 the horizontal flange at the top, as seen in Fig. 4. Preferably, and as the device is designed to be customarily used, the rail, C, will be inserted into the housing a sufficient 25 distance to bring one of the notches to the position for engagement by the edge of the wedge device when the latter is crowded up to wedging position, thus by the engagement of the edge of the wedge device in the notch insuring the rail against longitudinal 30 displacement. But whether engaged with the notch or with the edge of the rail between the notches, the wing nut, F, will be screwed up so as to crowd the sloping edges of both the wedge sides, d, firmly against 35 the edge of the rail, C, lodged on said sloping sides, whether it be the lower edge of the vertical web lodged on the slope, d^4 , or the inner edge of the horizontal flange lodged on the slope, d^3 . The width or distance 40 between the sides, d, of the wedge device, D, is preferably such that when the rail, C, is inserted to the utmost into the housing, both of said sides, d, may be engaged with the notches, 4, 4, or 4^a, 4^a; that 45 is, the notches are preferably spaced in accordance with said width of the wedge device. It will be observed that notwithstanding 50 the operation of the wedge device is to crowd the rail, C, up against the upper side, A², of the housing box, it is not found necessary to specially fortify this top side against being bent up by the crowding. This is because in the first place the crowding action operates on the top, A², of the 55 box immediately in or adjacent to the angle between said top and the outer side, and with minimum capacity, therefore, for bringing or bending it up; and, secondly, because this crowding action is effected by 60 means of a bolt whose head in crowding is

bound down upon the top of the box at a point farther from the angle than that at which the rail, C, is forced up against said top, so that the net effect of the clamping action would, in any event, be rather to bend 70 the top down than to force it up. Such down-bending is, of course, effectually prevented by the lodgment of said top upon the upper edge of the inner side wall, A¹, of the housing box, and is further prevented 75 by a cross bar, C¹, of the bed frame, which is an angle iron having its horizontal flange bolted to a lug, A⁵, struck out from the inner side of the wall, A¹, of the housing box and its horizontal flange bolted to a 80 lug, a², which projects from the inner edge of the top side, A², of the box.

The housing box, A, is secured to the corner post, B, by means of bolts, G, having their heads inside the post, and which are 85 therefore inserted from the inside of the post through the latter and through bolt holes, a⁴, in the back concavely curved wall or side, A⁶, of said housing box, the nuts being applied by means of a suitable key, 90 entrance for which to reach the nut on the upper bolt is provided through the forward wall, A⁷, of the housing box by the curved notch, a⁷, in the inner edge of the rectangular aperture which is provided in said wall 95 for admission of the intruded end of the side bar, C. The nut on the lower bolt is accessible by such key inserted below the lower edge of said forward wall, A⁷.

In order to stiffen the side bar, C, as much 100 as possible against the danger of bending horizontally, to which it is exposed in handling the bed bodily on the floor, the angle between the longitudinal and transverse 105 angles of the recess formed at the ends of the horizontal flange by cutting it back or narrowing it, as described, for insertion into the housing, is rounded as seen at c.

For guiding the wedge piece, D, accurately into place and in its movement in its 110 place when the thumb nut, F, is tightened to crowd said wedge piece against the edge of the side bar, lugs a³—a³ are struck in from the inner side wall, A¹, of the housing, said lugs being in a vertical line with each other 115 parallel with the forward wall, A⁷, of the housing against which the vertical edges, d^x, of the side, d, of the wedge device bear and are guided in the insertion and operation of said wedge device.

For convenience of entering the ends of the side bar, C, into the housing, the corners of both flanges, horizontal and vertical, are slightly beveled, as seen at c.

I claim:—

1. A bedstead corner fitting, comprising, in combination with a box-like housing having one vertical edge wall adapted to be applied and secured against the bedstead corner post, and the opposite vertical edge wall 130

apertured for admission endwise of a side rail, a wedge device mounted for sliding vertically in such housing, having an upwardly-facing sloping edge adapted to bear against the lower edge of a side rail entered endwise into the housing; a threaded bolt extending vertically in the housing and a nut on the lower end of the bolt which bears against the lower side of the wedge device for crowding the same upward to force its sloping edge against the side rail.

5 2. A bedstead corner joint comprising a housing box adapted to be mounted on the bedstead corner post and having the vertical edge wall opposite the corner post apertured to admit a side-rail; in combination with a wedging device mounted for sliding vertically in the housing box, having its wedging edge facing upward for encounter with the lower edge of the side rail, and means for forcing such wedging device up against and permitting it to withdraw from the side-rail.

10 3. A bedstead corner post comprising, in combination with an angle iron side rail having one flange reduced in width for a limited distance at the end; a housing box adapted to be mounted on the bedstead corner post and having its vertical edge wall apertured to admit the reduced end of the side rail either side up; a wedge device mounted for sliding vertically in the housing box with its wedging edge facing upward for encounter with the lower edge of the side rail, and means for forcing the wedging device upward and permitting it to withdraw for engaging and releasing the side rail.

15 4. A bedstead corner joint comprising, in combination with an angle iron side rail; a housing box adapted to be mounted on the bedstead corner post and having its vertical edge opposite the corner post apertured to admit the side rail endwise; a wedging device mounted for sliding vertically in the housing box with its wedging end facing upward for encounter with the lower edge of the side rail, said lower edge having a plurality of notches spaced apart along the portion of the edge which may be intruded into the housing box for engagement of the wedging device.

20 5. A bedstead corner joint comprising, in combination with an angle iron side rail having one flange reduced in width for a limited distance at the end; a housing box adapted to be mounted on the bedstead corner post having its vertical edge wall opposite the corner post apertured to admit the reduced end of the side rail either side up; a wedge device mounted for sliding vertically in the housing box having its upper edge sloped to face upwardly and outwardly toward the side rail, said edge comprising two slopes with an intermediate offset or

step, said slopes being positioned for engaging respectively the edge of the vertical flange and the edge of the reduced horizontal flange in the two respectively inverted positions in which said side rail may be inserted into the housing.

25 6. A bedstead corner joint comprising, in combination with an angle iron, side rail having one flange reduced in width for a limited distance at each end; a housing box adapted to be mounted on the bedstead corner post having its vertical edge wall opposite the post apertured to admit the reduced ends of the side rail, either side up; a wedge device mounted for sliding vertically in the housing box having a sloping edge facing upward and outward toward the side rail, and comprising two slopes and an intervening offset or step, said slopes positioned for engaging respectively the edge of the horizontal and the edge of the vertical flange of the side rail at the two respectively inverted positions of the latter, said edges having each a notch positioned for engagement of the wedge device at the fully inserted position of the side rail in the housing.

30 7. A bedstead corner joint comprising, in combination with an angle iron side rail having one flange considerably reduced and the other flange slightly reduced in width for a limited distance at the ends, said reductions forming stop shoulders for limiting the insertion of the side rail into a housing box, such housing box adapted to be mounted on the bedstead corner post having its vertical edge wall adapted to admit the reduced end of the side rail to said shoulders; a wedging device mounted for sliding vertically in the housing box having a sloping edge face upward and outward toward the side rail, said edges of the side rail having each a notch positioned for engagement of the sloping edge of the wedging device when the side rail is inserted in the housing to said shoulders.

35 8. A bedstead corner joint comprising a housing box adapted to be mounted upon the bedstead corner post, having its vertical edge wall opposite the post apertured to admit a side rail endwise; a wedging device mounted for sliding in the housing box, consisting of a bar having up-turned end portions sloped for wedging and having vertical edges parallel for guidance in the box upon the side walls of the latter; a bolt extending vertically through the housing engaging the cross bar of the wedging device, and a nut on the bolt for crowding the wedging device against the side rail.

40 9. A bedstead corner joint comprising a housing box adapted to be mounted on the bedstead corner post and consisting of a metal plate folded to inclose four longitudinal sides, two vertical and two horizontal, and to form a vertical edge wall, the upper

horizontal side being lapped upon the edge of the inner vertical side; the said vertical edge wall being apertured to admit a side rail endwise in position to seat sidewise 5 against the outer vertical side wall of the box, and upward against the upper horizontal wall; a wedging device mounted for sliding vertically in the box having a sloping edge facing upward and outward for 10 counter with the lower edge of the side rail to crowd it into the upper outer corner of the box; and a threaded bolt which takes through the upper horizontal wall of the box and vertically through the wedging device 15 for forcing the wedging device toward said top wall.

10. A bedstead corner joint comprising a housing box adapted to be mounted on the bedstead corner post and consisting of a 20 metal plate folded to inclose four longitudinal sides, two vertical and two horizontal, and to form a vertical edge wall, the upper horizontal side being lapped upon the edge of the inner vertical side; the said vertical 25 edge wall being apertured to admit a side rail endwise in position to seat sidewise against the outer vertical side wall of the box, and upward against the upper horizontal wall; a wedging device mounted for 30 sliding in the housing box, consisting of a

bar having up-turned end portions sloped at their upper edges for facing upward and outward toward the side rail, and a bolt which extends through the top wall of the box through the cross bar of the wedging 35 device, and a nut on the bolt below the wedging device for drawing the top wall and the wedging device toward each other.

11. In combination with a hollow bedstead corner post, a corner fitting comprising a housing box having one vertical edge wall adapted to seat against the post, the post and said wall having registering bolt-holes, the opposite vertical edge wall being apertured to admit a side rail endwise; a 40 bolt which secures the housing to the post inserted from within the post and protruding into the housing cavity, and a nut on said bolt within said cavity, the vertical edge wall through which the side rail is 45 inserted having the aperture for said rail extended to admit a key to operate the nut.

In testimony whereof, I have hereunto set my hand at Chicago, Illinois; this 25th day of February, 1914.

MORRIS B. OKUN.
